HAND-GRIPPING TOOL

Leon D. Clark, Skiatook, Okla.

Application March 31, 1944, Serial No. 528,901

4 Claims. (Cl. 81—86)

This invention relates to a hand-gripping tool, and it is primarily an object of the invention to provide a tool which constitutes a wrench of a plier type.

It is also an object of the invention to provide a tool of this kind which readily permits visible settings, whereby the efficiency of the tool is materially increased and wherein the tool is constructed in a manner resulting in a substantial saving of material without sacrificing the effectiveness of the tool.

A still further object of the invention is to provide a tool of this kind including a sliding jaw, together with positive stops for limiting the movement of such jaw, and wherein the operating member of the sliding jaw coacts therewith in a manner to maintain said movable jaw in applied or working position.

The invention consists in the details of construction and in the combination and arrangement of the several parts of my improved hand-gripping tool whereby certain important advantages are attained, as will be hereinafter more fully set forth.

In order that my invention may be better understood, I will now proceed to describe the same with reference to the accompanying drawing, wherein:

Figure 1 is an elevational view of a hand-gripping tool constructed in accordance with an embodiment of my invention;

Figure 2 is a front elevation of the device as illustrated in Figure 1;

Figure 3 is a fragmentary elevational view of the inner face of the holding head as herein embodied;

Figure 4 is a fragmentary edge elevational view of the head carrying the fixed jaw;

Figure 5 is a view in side elevation of the sliding jaw, unapplied; and

Figure 6 is a view in end elevation of the structure illustrated in Figure 5.

As disclosed in the accompanying drawing, 1 denotes a flat head of desired dimensions and which has its outer margin a of material length and substantially straight. The head 1 at one edge portion of this margin a has integrally formed therewith an outstanding fixed or integral jaw 2 which is of a width to extend the desired distance beyond the straight edge a of the head 1.

The under or inner face of this extended portion of the jaw 2 is undercut, as at 3, to snugly receive the upper beveled edge face b of the elongated shank 4 extending laterally from the lower portion of a sliding jaw 5. This shank 4 at its

lower portion is provided with a laterally directed guide flange 6 which snugly engages within a groove or channel 7 in the face of the head 1 beyond which the fixed jaw 2 extends.

5 The under longitudinal margin of the shank 4 is provided with a series of equidistantly spaced notches 8 into which is adapted to be selectively received an outstanding tooth 9 radially disposed with respect to an arcuate edge face 10 of a head 11 carried by an end portion of a lever 12.

10 This selective engagement of the tooth 9 within a notch 8 permits of a desired adjustment of the relative setting of the jaws 2 and 5 as determined by the size of the work with which the tool is to be employed. The head 11 of the lever 12 is provided along its arcuate edge face 10 with an outstanding flange 14 which overlies the outer face of the shank 4 whereby the shank 4 together with the movable jaw 5 carried thereby is effectively held and maintained in desired assembled position without requiring any boxlike structure as previously in common use through which the shank is slidably directed.

15 The head 11 is pivotally held in desired position upon the head 1 by the removable pivot member 15. By oscillating the head 11 to a sufficient extent by swinging the handle 12 outwardly, the desired adjustment of the jaws 2 and 5 may be readily effected and in order to facilitate such adjustment, the outer face of the shank 4 is provided with the gauge lines 16. These lines are so placed that when the tooth 9 is free from the notches 8, a quick adjustment of the head may be made by locating one of the lines at the edge of the face of the fixed jaw 2, which results in locating the notches 8 so that the tooth will move directly into a notch when the handles are closed.

20 The head 1 below the groove 7 and to one side of the pivotal mounting between the heads 1 and 11 is provided with an outstanding stop lug 17 with which engages a depending lug 18 at the extremity of the shank 4 remote from the removable jaw 5 whereby the extent of sliding movement of the jaw 5 away from the jaw 2 is positively limited.

25 The head 1 is herein disclosed as rigid with the second lever 19 which coacts in a well known manner with the lever 12.

30 The marginal portions of the heads 1 and 11 are provided with the coacting notches 20 whereby the tool, when desired, may be employed as a wire cutter and the outer extremity of one of the operating levers 19 is formed to provide a blade 22 to enable said lever to be conveniently used as a screw-driver.

From the foregoing, it is believed that the tool is one which provides a pair of powerful parallel plier jaws whereby the tool, when desired, can be effectively used as a hand vise and by a linesman as a splicing clamp. The tool is also one which can be readily employed as a pipe wrench and also to be effectively used as an adjustable wrench with sufficient strength to hold a nut without relative opening movement of the jaws with the resultant cutting of the corners of the nut.

It is also to be pointed out that the sliding jaw 5 is extended to overlie the straight margin *a* of the head 1 and that said extended portion of the jaw 5 has its under edge face undercut to snugly receive the inward and upward bevel of said straight margin *a*, whereby the sliding jaw is further effectively maintained in applied or working position.

From the foregoing description it is thought to be obvious that a hand-gripping tool constructed in accordance with my invention is particularly well adapted for use by reason of the convenience and facility with which it may be assembled and operated.

What is claimed is:

1. A tool of the class described comprising two overlying heads, means for pivotally connecting one head to the other, levers carried by said heads and extending in the same general direction to provide means for rotating one of the heads relative to the other, a fixed jaw extending outwardly from one of the heads, the margin of said one head to one side of the jaw being substantially straight, a face of said one head being provided with a guide groove parallel to said substantially straight margin, a shank having a guide flange extending within the groove, a jaw extending from one end portion of the shank in the same general direction as the fixed jaw, and an operative connection between the second head and the shank for imposing endwise movement to the shank upon relative rotation of the heads, said second head being provided with an outstanding flange por-

tion overlying the shank to hold the shank and the jaw carried thereby in working position.

2. A tool of the class described comprising two overlying heads, means for pivotally connecting one head to the other, levers carried by said heads and extending in the same general direction to provide means for rotating one of the heads relative to the other, a fixed jaw extending outwardly from one of the heads, the margin of said one head to one side of the jaw being substantially straight, a face of said one head being provided with a guide groove parallel to said substantially straight margin, a shank having a guide flange extending within the groove, a jaw extending from one end portion of the shank in the same general direction as the fixed jaw, an operative connection between the second head and the shank for imposing endwise movement to the shank upon relative rotation of the heads, said second head being provided with an outstanding flange portion overlying the shank to hold the shank and the jaw carried thereby in working position, a stop lug carried by the first head to one side thereof, and a lug depending from the shank at the extremity thereof remote from the second head for contact with the first lug to limit the extent of opening movement of the jaw of the shank.

3. A tool as set forth in claim 1, wherein the operative connection between the second head and the shank comprises longitudinally spaced notches in the shank, and a tooth carried by the second head selectively engaging in one of the recesses and wherein the mounting of the heads is releasable.

4. A tool as set forth in claim 1, wherein the operative connection between the second head and the shank comprises longitudinally spaced notches in the shank, a tooth carried by the second head selectively engaging in one of the recesses and wherein the mounting of the heads is releasable, and means carried by the shank to facilitate locating a notch in position to receive the tooth.

LEON D. CLARK.
